UNITED STATES PATENT OFFICE

2,506,508

DEVICE FOR HOLDING WINDOWS

Myros Kmita, Abernathy, Saskatchewan, Canada

Application January 21, 1947, Serial No. 723,361

2 Claims. (Cl. 292—288)

1

This invention relates to improvements in devices for holding windows in the desired raised or open position.

An object of the invention is to provide an improved adjustable device for holding a window sash in the desired raised or open position.

Another object of the invention is to provide an improved step by step adjustable device for positioning in a window frame below a vertically adjustable window sash for holding the same in the desired raised or open position.

A further object of the invention is to provide a telescoping step by step adjustable window sash supporting device adapted to be placed between the window frame and the lower surface of a window sash for positively holding the sash at the desired open or raised position.

Another object of the invention is to provide an improved window sash supporting device which will be highly efficient in operation, and relatively inexpensive to manufacture and produce.

Other objects will appear as the description proceeds.

In the accompanying drawings which form a part of this application,

Figure 1 is a perspective view of the improved adjustable window sash holder shown in operative position between a window frame and the lower sash therefor;

Figure 2 is a perspective view of the notched base portion of the adjustable window holding device;

Figure 3 is a perspective view of the lower end of the base portion of the window holding device showing the hinged base plate secured thereto in lowered position;

Figure 4 is a side elevation of the base portion of the window holding device showing the step by step adjustable upper portion in section, with a window sash shown in dotted lines being supported in open position by said device;

Figure 5 is a perspective view of the upper portion of the window holding device, and

Figure 6 is a perspective view of the upper end of said upper portion of the window holding device, showing the sash supporting angle plate pivotally attached to the upper end thereof and moved to its outermost position.

Like characters of reference are used throughout the following specification and the accompanying drawings to designate corresponding parts.

In carrying out the invention, there is provided an improved window sash supporting and holding

2

device comprising a substantially rectangular vertically extending base portion or member generally designated by the reference numeral 1, the same being formed in its forward edge with a plurality of vertically spaced inwardly extending locking notches 2 having flat seats 3 forming the base portions of said notches.

A pair of base supporting plates 4 and 5 are hinged at 6 and 7 respectively to the opposite sides of said base member 1 for extending outwardly at the opposite sides of the lower end of said member 1 when the same is placed in position upon a window sill 8 of a window frame 9, when the device is to be used for supporting or holding a window sash 10 in the desired raised position.

The U-shape top or upper channel member 11 of the sash supporting and holding device is made from metal, and is open on one side, the same being adapted to telescope and slide upwardly and downwardly upon the close fitting base member 1, and is formed with the oppositely disposed forwardly extending parallel arms 12 and 13 adjacent its lower end. The arms 12 and 13 are formed with the depending ears 14 which support the pin 15, upon which the double ended pawl or dog 16 is pivotally mounted.

A pin 17 is connected between the outer ends of the arms 12 and 13 and supports one end of a coil tensioning spring 18, whose opposite end is connected with the pawl or dog 16 for normally urging the inner end thereof in a downward direction to seat on and engage the selected seat 3 forming part of the notches 2 in the base or lower member 1 of the window holding device.

The upper edges of the parallel arms 12 and 13 are disposed in horizontal flat position and are adapted to underlie and support the window sash frame 10 when the same is in open or raised position.

A metal angle window sash supporting plate 19 is pivoted upon the pin 20 to one side of the upper channel member 11, and is adapted to be swung over the end of said member to underlie the bottom of the window sash frame 10 when the sash is to be supported in open position above the limits of the sash supporting arms 12 and 13, as illustrated in Figure 1 of the drawings.

In operation, the window sash will be raised to the desired height, and the supporting and holding device placed thereunder, after which the upper channel member 11 will be moved upwardly until the lower surface of the sash frame is seated upon the parallel sash supporting arms, and the pawl or dog 16 is engaged on the nearest 55 adjacent seat 3 in the proper notch 2.

As before mentioned, the parallel arms 12 and 13 will support the lower window sash in a step by step manner until the sash has been raised approximately one-half of its full or open position, and for supporting the sash from that point until it is fully open, the sash will be seated upon the pivoted plate 19 disposed upon the upper end of the top member 11.

From the foregoing description, it will be seen that there has been devised and provided a highly efficient form of device for supporting and holding window sashes in the desired open position.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A device for holding windows in raised position comprising a base member having laterally extending base plates a plurality of spaced inwardly extending notches having lateral shoulders, disposed in a vertical edge of the member, a U-shape channeled member slidably disposed on said base member, window sash supporting arms extending integrally from the channeled member, a pivoted locking pawl associated with said arms for selective engagement with said notches and seats for holding said channeled member in the desired adjusted position, resilient means connected between said arms and said pawl

for adjustably retaining said pawl in engagement with the desired shoulder, and a window sash supporting plate pivotally supported upon the forward edge of one side of said channeled member and adapted to be swung over the top of said channeled member to provide a supporting seat for a window sash.

2. A device for holding windows in raised positions comprising an elongated bar, laterally extending pivoted base plates disposed at one end of the bar for supporting the bar in a vertical position, said bar being formed at one edge with a plurality of vertically spaced notches, an elongated channel member slidably disposed on said bar and having its open side aligned with the notches, a pair of parallel arms laterally extending from said open side of the member, a pawl pivotally mounted between said arms and resilient means connected between the outer end of the pawl and the arms for retaining the inner end of the pawl in engagement of the notches and a window sash supporting plate pivotally carried by the upper end of the member.

MYROS KMITA.
